Frank H. Allen.

UNITED STATES PATENT OFFICE.

GEORGE F. BARD, OF NORWICH, CONNECTICUT.

NIPPLE-HOLDER.

SPECIFICATION forming part of Letters Patent No. 527,168, dated October 9, 1894.

Application filed April 21, 1894. Serial No. 508,549. (No model.)

To all whom it may concern:

Be it known that I, GEORGE F. BARD, a citizen of the United States, residing at Norwich, in the county of New London and State of Connecticut, have invented a certain new and useful Improvement in Nipple-Holders, which improvement is fully set forth and described in the following specification, reference being had to the accompanying sheet 10 of drawings, in which—

Figure 1 is a side view of said nipple holder and Fig. 2 an outer end view of the same. Fig. 3 shows the same principally in central, longitudinal, section on line $x-x$ of Fig. 2. Fig. 4 is a view similar to that of Fig. 3 illustrating particularly the outer (sliding) shell c and Fig. 5 shows inner side and end views of one of the jaws of my nipple holder. Fig. 6 is a cross sectional view of the shank of 20 said holder taken on line $x'-x'$ of Fig. 3. In Fig. 7 I have shown a nipple of the form my device is adapted to hold.

This invention seeks to provide a simple clamping device, of expandible chuck form, 25 by means of which sections of pipe, or so called nipples, may be securely held during the act of threading the same; my said device being so constructed that previously threaded pipe-ends may be clamped without jamming 30 or upsetting such threads.

In producing this holder I have kept in mind three important results to be attained; first, a chuck that will hold the threaded nipple firmly without injuring it, second, one 35 that may be quickly and easily operated without recourse to special wrenches or other tools and, third, one in which different sizes of holding jaws may be readily adjusted and used.

40 In the accompanying drawings the letter a indicates a shank or mandrel that is squared near one end, as at a' leaving a head a^2 against which the nipple end may abut when the device is in service.

45 The letters b denote jaws whose outer surfaces are tapered from front to rear and whose inner surfaces are chambered as at b' to fit the perimeter of the shank a , the portion b^3 intervening said chambers being 50 adapted to fit the flat faces of the square portion a' of said shank, so that when the several jaws are assembled around the shank-end they are held against endwise and rotary displacement on said shank. The tapered 55 outer faces of the jaws, when assembled, form

a frustum of a cone upon which is loosely mounted a correspondingly tapered collar c whose rear portion fits loosely on shank a . Whenever the collar c is forced outward (that is, toward the holding ends of the jaws) the 60 jaws are forced together after the manner of ordinary drill chucks and to thus move the collar, as well as to lock the same, I have provided a key d , of wedge shape, that is seated in a slot d' in shank a , immediately in the 65 rear of the collar.

By placing the larger end of the cone outward and locating the sleeve between the wedge and the cone, or to the rear of the cone, the end of the cone never projects beyond the outer end of the sleeve, which would have a tendency to interfere with the insertion of the nipple between the jaws, as would happen if the smaller end of the cone were outward and the sleeve would have to be 75 slipped outward to loosen the jaws.

When wedge d is driven home in its seat it crowds the several jaws together, thus firmly clamping between them a nipple, or other article, placed within said jaws. To release 80 the jaws it is only necessary to drive the wedge d out of its seat, when collar c slips away from the taper jaws and the latter are at once released. For holding threaded nipple ends the jaws should be correspondingly 85 threaded as shown, so that any tendency of the nipple to turn within the jaws may not result in jamming the thread.

Different sets of jaws, having their open ends bored and tapped to hold nipples of 90 various sizes may be fitted for use with a single shank, collar and key, thus reducing materially the outlay necessary for providing holders for such different sizes.

To prevent the loss of key d I drive, or 95 screw, a pin d^2 through its smaller end.

Having described my invention, I claim—

A nipple holder consisting of a shank squared adjacent one end as at a' , a set of cone-shaped jaws each being chambered at 100 each end and having an intermediate portion as b^3 formed to engage said shank as set forth, a collar mounted to slide on said jaws and a device substantially as described for moving said collar to close the jaws.

GEORGE F. BARD.
